ANTENNA COMPENSATOR

Chester L. Davis, Keokuk, Iowa, assignor to
Wired Radio, Inc., New York, N. Y., a corpora-
tion of Delaware

Application July 24, 1930. Serial No. 470,461

7 Claims. (Cl. 250—33)

My invention relates broadly to radio signaling systems and more particularly to the construction of a device adapted for connection in circuit with an antenna conductor for compensating for the effects of temperature changes 5 upon such conductor.

One of the objects of my invention is to provide a construction of antenna compensator for maintaining constant frequency operation of an 10 antenna conductor independent of changes in temperature conditions.

Another object of my invention is to provide a construction of compensator for connection in circuit with an antenna conductor for effectively 15 compensating for changes in length of the antenna conductor under conditions of variations in temperature.

A further object of my invention is to provide a construction of antenna compensator for 20 correction for variations in frequency characteristics of an antenna system for variations in temperature conditions by arranging thermal expansion means directly adjacent the antenna conductor and subjecting the antenna conductor to changes in frequency characteristics equal and 25 opposite to normal changes due to variations in temperature.

Other and further objects of my invention will 30 be understood from the specification hereinafter following by reference to the accompanying drawings in which:

Figure 1 is a perspective view of the antenna compensator and associated rigging used in signaling systems; Fig. 2 is a longitudinal section taken through one form of antenna compensator 35 employing the principles of my invention; Fig. 3 is a transverse vertical section taken on line 3—3 on Fig. 2; Fig. 4 is a theoretical view illustrating the principles involved in the antenna compensator of my invention, the impedance element being shown in elevation; Fig. 5 is a sectional view of a modified form of antenna compensator embodying the principles of my invention with parts shown in elevation; Fig. 6 is a longitudinal cross-sectional view through the antenna compensator with parts illustrated in section 40 1; Fig. 7 is a cross-sectional view taken through the thermostatic control device in the compensator system of Figs. 5 and 6 on line 7—7 of Fig. 6; Fig. 8 is a cross-sectional view taken 45 on line 8—8 of Fig. 6; Fig. 9 is a cross-sectional view on line 9—9 of Fig. 6; and Fig. 10 is a theoretical view illustrating the principle of operation of the antenna compensator illustrated in 50 Figs. 5—9.

Referring to the drawings, reference character 1 designates the antenna conductor which is secured to the eyelet member 6 in one end of the cylindrical member 2. In the form illustrated in Fig. 2 this casing may be made of insulation material. In the modification illustrated in Figs. 5—9 the casing may be made of conductive material. The rigging for the device of my invention as shown in Fig. 1 is such that the compensator is insulatingly supported by 60 means of insulator 3 with respect to halyard 4 and supporting mast 5. The cylindrical casing 2 is closed at one end by member 7 which may be screw threaded to engage interior screw threads on the inside walls of casing 2 with pins 65 8 projecting radially into the end of plate 7. The ring member 9 extends through the end plate 7 for securing insulator 3 thereto. An insulated support 10 is spacially mounted by suitable means designated at 11 in a position spaced 70 from the interior walls of the casing 2. The member 10 is wound by the turns 12 of an inductance which is connected at one end with the end of the antenna conductor 1 as indicated at 13. The end 13 of the inductance 12 is also 75 connected to the end of the thermometer 25. The inductance 12 is tapped along the length thereof to connections which extend into the bore of the thermometer at 14, 15, 16, 17, 18, 19, 20, 21 and 22. The thermometer is suitably secured 80 to the interior wall 2 and assumes the temperature of the surrounding atmosphere. In order that the thermometer 25 will at all times be retained in its lowest position, I provide a weighted 85 fin 2' on the casing 2 which maintains the casing 2 in a predetermined position. As changes 90 occur in the length of the antenna 1 due to changes in temperature corresponding changes occur in the thermometer 25 and as the mercury therein expands the several taps along the inductance 12 are electrically shunted thus serving 95 to reduce the effective period in proportion to the increase in period of the antenna conductor 1. Frequency variations in the antenna conductor 1 are accordingly compensated by 100 frequency variations in inductance 12. That is, for changes in frequency characteristics in antenna 1 there are equal and opposite changes in frequency characteristics in the inductance 12 according to temperature changes. Variations 105 in signaling frequency are thereby avoided by maintaining an antenna of constant frequency characteristics independent of temperature changes.

In Figs. 5—9 I have shown a conductive tubu- 110

lar member 26 surrounding the inductance 12. Adjacent one end of the tubular member 1 arange a spiral bi-metallic strip 27 having portions 27a and 27b of materials having different coefficients of expansion. The center of the bi-metallic strip 27 is connected to the connecting ring 6 and the end 12b of the inductance 12. A strip of insulation 28 is provided on the exterior surface of a number of the convolutions of the bi-metallic strip 27 preventing electrical short-circuit with the interior walls of the tubular casing 26. A guide member 31 in the form of a disc centers the bi-metallic strip in position and allows the expansion and contraction thereof.

15 As the temperature increases the bi-metallic strip expands and moves closer to the interior wall of tubular member 27. The end of the inductance 12 is connected to the bi-metallic strip 27 as represented at 12a. The expansible strip 20 serves as illustrated in Figs. 7 and 8, to vary the capacity across the ends of the fixed inductance 12. That is as the temperature rises the bi-metallic strip expands and the capacity increases due to the decrease in spacial relation between the bi-metallic strip 27 and the inner walls of the tubular member 26. The inductance 12 is therefore tuned to a frequency characteristic compensating for changes in frequency in conductor 1 under conditions of temperature change. As 25 the temperature decreases the bi-metallic strip 27 contracts thereby increasing the effective capacity across the inductance 12 and compensating for the reduction in length of the antenna conductor 1.

30 While I have described my invention in certain preferred embodiments I desire that it be understood that modifications may be made and that no limitations upon my inventions are intended other than are imposed by the scope of the appended claims.

35 What I claim as new and desire to secure by Letters Patent of the United States is as follows:

1. An antenna compensator comprising a suspension member connected with an antenna conductor said suspension member including an inductance device electrically connected in series with the antenna conductor and forming an electrical extension thereof and thermostatic means connected with said inductance device for varying the frequency characteristic thereof for compensating for changes in frequency of said antenna conductor under conditions of variable temperature.
2. An antenna compensator comprising a suspension member connected with an antenna conductor said suspension member including an inductance device electrically connected in circuit with the antenna conductor, and forming an electrical extension thereof and thermally responsive means connected with said inductance device for changing the frequency characteristics thereof in an opposite sense to the normal change in frequency characteristics of said antenna conductor under conditions of variable temperature.
3. An antenna compensator comprising a suspension member connected with an antenna conductor said suspension member including an inductance device electrically connected in series with the antenna wire and forming an electrical extension thereof, a thermally responsive device carried by said suspension member and electrically connected with said inductance device, said thermally responsive device being disposed adjacent said inductance device for changing the 75 capacity across the ends thereof and modifying

the frequency characteristics of said antenna conductor for compensating for the effects of temperature changes upon said antenna conductor.

4. An antenna compensator comprising a casing member, means at one end of said casing member for suspending said casing member, means at the other end of said casing member for supporting an antenna conductor, a weight attached to said casing member for predetermining the position thereof when in suspension, an inductance device mounted within said casing member and electrically connected with said antenna conductor, and a thermostat disposed within said casing member immediately above the weighted portion thereof and electrically connected with said inductance device for predetermining the effective value of inductance in circuit with said antenna conductor.

5. An antenna compensator comprising a casing member, means at one end of said casing member for suspending said casing member, means at the other end of said casing member for supporting an antenna conductor, a weight attached to said casing member for predetermining the position thereof when in suspension, an inductance device mounted within said casing member and electrically connected with said antenna conductor, and a thermostatically controlled variable condenser disposed within said casing member and electrically connected in shunt with said inductance for predetermining the frequency characteristics of said inductance in series with said antenna conductor in accordance with conditions of temperature.

6. An antenna compensator comprising a conductive tubular casing, suspension means connected to one end of said casing, an antenna conductor connected to the opposite end of said casing, a partition member laterally dividing said casing into separate sections, an inductance insulatingly spaced from the interior walls of said casing member and having one end electrically connected with said antenna conductor and the other end connected with said tubular casing in one of the sections thereof, a thermostatically controlled capacity element mounted in the other of the sections of said casing member, said capacity element being variable in the spacial relation thereof with respect to the interior walls of said tubular casing for controlling the frequency characteristics of said inductance in series with said antenna conductor in accordance with temperature conditions.

7. An antenna compensator comprising a suspension member, supporting means connected to one end of said suspension member, an antenna conductor connected with the other end of said suspension member, an insulated support extending axially through said casing member, an insulated spider disposed between each end of said insulated support and the interior walls of said casing member, an inductance wound on said insulated support and connected at one end thereof with said antenna conductor, a mercury thermostat disposed beneath said inductance and within said casing member, contacts arranged at spaced intervals along said mercury thermostat and connected with taps on said inductance, and means for gravitationally maintaining said thermostat beneath said inductance while said casing member is suspended.

CHESTER L. DAVIS.
